LADY'S HAT

Herbert Bentley, New York, N. Y.

Application August 29, 1942, Serial No. 456,579

6 Claims. (Cl. 2—176)

The present invention relates to ladies' hats, and has for one of its objects the provision of a head covering having a knitted or crocheted band between the crown and brim to produce various ornamental and decorative effects and attractive designs and without the addition of extraneous materials.

A further object is to provide in a lady's hat, an elastic knitted or crocheted band between the crown and brim, so that a given hat may fit a relatively wide range of head sizes, said band, furthermore, providing a third zone or level of interest.

A further object is to provide in a lady's hat, an ornamental and decorative zone of interest which may serve to permit air to circulate within the interior of the hat when the same is worn.

With the foregoing features and objects in mind, and many others which will later become apparent, the invention resides in the novel constructional details and in their novel combination and arrangement as illustrated in the accompanying drawing in which is depicted embodiments of the invention as at present contemplated.

In the drawing:

Fig. 1 is a perspective view of a lady's hat showing one form of the invention.

Fig. 2 is a section on line 2—2 of Fig. 1.

Fig. 3 is a fragmentary portion of preferred stitching for uniting the knitted band to the felt portions.

Fig. 4 is a similar view but showing a modified form of stitch.

Fig. 5 is a fragmentary sectional view showing a modification of the hat shown in Fig. 1.

Referring now to the drawing in further detail and to the preferred form of the invention illustrated in Fig. 1, it will be seen that the hat comprises a crown 1, an elastic knitted or crocheted band 2, and a brim 3. The band 2 may be knitted or crocheted in advance as a separate unit, and joined to the crown and brim respectively, or the band may be knitted or crocheted as a continuation of the initial operation of joining the band to be knitted, to the crown (or brim, as the case may be).

In the preferred form illustrated in Fig. 1, the inner edge of the brim is sewn around its periphery along a line around the band intermediate the top and bottom edges thereof, as more clearly explained and illustrated hereafter.

In speaking of the knitted band being between the crown and the brim, I mean that there is an hiatus between the two, the aforesaid knitted

band comprising a liaison member between the two elements; said band being exposed and visible to others, and susceptible of varied design, pattern and color.

5 One way in which the band 2 may be joined to the crown (or brim) is shown in Fig. 3, wherein the said crown (or brim) is perforated or punctured as at 4, 4, at spaced points around the inner periphery, said punctures being positioned a predetermined distance from the edge 5 of the crown (or brim). A strand or thread 6 of yarn may be threaded through, or hooked over a hooked needle and then passed through, said perforations or punctured spots successively or otherwise, in a winding manner, as illustrated in Fig. 2—that is, over, under and around the edge of the crown or brim, as the case may be. The puncturing may be done as an incident to reeling and coiling the strand of yarn around said crown or brim. Where 10 the band proper is yet to be knitted then the strand 6 is left rather loosely woven in order that a subsequent strand 7, forming the next row of the band to be formed, may be looped or passed through the coils or loops of the strand and in 15 this way accomplish the joining of the band to the crown or brim.

In Fig. 4, I have illustrated a modified form of initial "anchoring" strand of yarn 8. In this case, the brim and the crown or either of them, 20 are first perforated as at 4^a and a single strand of yarn is engaged by a hooked needle (not shown) and pulled through the said perforations or apertures to provide a series of loops 9 depending from and around the crown (or brim), so 25 that a subsequent strand 10, forming the first row of the band proper, may be passed through said loops, in a well-known manner, and thus joined to the crown or brim, as the case may be.

If the band be separately prepared, it may be 30 joined to the crown and brim or to either of them in the manner suggested by Fig. 2 or by stitching it to the respective portions of the hat.

In order to add variety to chic, the arrangement of the various parts may be changed to 35 suit the taste of the designer. In Fig. 1, the brim 3 is joined by a line of stitching 11 to the band along a line around and intermediate the top and bottom edges thereof.

40 In the modification illustrated in Fig. 5, the band 2 is crocheted or knitted directly to the crown 1 and to the brim 3 and a sweat band 12 is stitched to the inside of the hat in the customary manner.

45 Having thus described my invention, what I

claim as new and desire to secure by Letters Patent, is:

1. A lady's hat comprising a crown, a brim, and an exposed and visible elastic knitted band intermediate and joining said crown and brim, and extending below said brim to constitute a head band for the hat.

2. A lady's hat comprising a crown, an elastic knitted band depending therefrom, and a brim joined to said band along a line around said band between the top and bottom edges thereof, the bottom edge of said band constituting the head band of said hat.

3. A lady's hat comprising a crown, a brim, and an exposed and visible elastic knitted band adapted to engage the head of a wearer as a head band for said hat, said band being partly positioned intermediate and joining said crown and brim respectively and providing a third zone or unit of interest.

4. A lady's hat comprising in combination a crown, a non-continuous brim and a knitted band

intermediate the adjacent edges of said crown and brim, said band constituting an elastic head band for said hat.

5. A lady's hat comprising in combination, a crown having at least its lower head band portion of knitted material, and a non-continuous brim having its inner edge connected to said band intermediate the edges thereof.

6. A hat comprising a crown section having an annular edge portion with a line of spaced perforations near the edge thereof and extending completely around said annular edge, a knitted band forming a continuation section from said annular edge portion, the band being knitted directly to the crown through said perforations to secure the band to the crown, and a brim member having a line of spaced perforations near its inner edge, the band being knitted to the brim through said perforations to secure the brim to the band, whereby the band presents an intermediate zone spacing the crown and brim.

HERBERT BENTLEY.
